CHARLES C. GERHART, OF CLARKSVILLE, TENNESSEE.

DUST-HOOD FOR HOT-AIR REGISTERS.

1,113,428.

Specification of Letters Patent.

Patented Oct. 13, 1914.

Application filed December 12, 1913. Serial No. 806,169.

To all whom it may concern:

Be it known that I, CHARLES C. GERHART, a citizen of the United States, residing at Clarksville, in the county of Montgomery 5 and State of Tennessee, have invented a new and useful Dust-Hood for Hot-Air Registers, of which the following is a specification.

My invention relates to a dust hood for 10 hot air registers applicable to registers or radiators located in the floor of a room, or, if my hood is provided with suitable supporting means, to registers or radiators located in the side walls of a room, and the 15 objects of my invention are first, to provide a dust hood for hot air registers, in which the hot air from the heating source on entering the hood is caused to circulate and the dust, soot, ashes, lint or other matter therein 20 to be deposited and retained on an air screening means and the purified air then transmitted to the room; second, to provide a dust hood for hot air registers having means for moistening the hot air passing 25 therethrough, and further causing, through such moistening of the hot air, the dust, ashes, lint or other matter in the hot air to cling the closer to the inside of the top or cover and to the air screening means of 30 the hood; third, to provide a dust hood for hot air registers that prevents the hot air from the heating source from coming into injurious contact with the walls or ceiling of the room, thus preventing the soiling, 35 smudging or scorching of the walls, wall paper, wood work or ceiling of the room; and fourth, a dust hood for hot air registers which may be used in conjunction with oil or gas heaters for moistening the hot air 40 emanating therefrom and concentrating the heat at the top thereof and distributing it in a desired direction in the room. I accomplish these objects by the device illustrated in the accompanying drawings in which—

45 Figure 1, is a side elevation of my dust hood for hot air registers. Fig. 2, is a sectional plan view of my dust hood for hot air registers on the line 2—2 of Fig. 1. Fig. 3, is an end elevation of my dust hood 50 for hot air registers. Fig. 4, is a view of my dust hood for hot air registers on the line 4—4 of Fig. 1.

Similar numerals refer to similar parts throughout the several views.

55 My dust hood for hot air registers, which is made of tin, galvanized iron or other suit-

able material, comprises a box frame, open at its bottom, having sides, 10, and ends, 11, a top or cover, 12, a hot air outlet, 13, an air screening ledge or shelf, 14, and a 60 water trough, 15.

The box frame is preferably rectangular in shape, the sides, 10, and ends, 11, of the box frame being attached at their lines of meeting by soldering or in other suitable 65 manner, the manner of attachment shown in the drawings being the joining of lapping portions of the sides and ends formed by bending at an angle the edge of the sides or ends. The box frame is open at its 70 bottom to permit placing of the dust hood over the register or radiator, the open bottom being of sufficient size to cover the hot air area of the register or radiator so as to receive all the hot air therefrom. The box 75 frame is provided with longitudinals, 16, and cross pieces, 17, to strengthen it at its bottom, the rear longitudinal, 16, and the cross pieces, 17, being formed by turning over at an angle the lower edge of the rear 80 side, 10, and the lower edges of the ends, 11, of the box frame, but I do not restrict myself to this form, as any suitable manner of providing longitudinals and cross pieces 85 may be employed.

The front side or face, 10, of my dust hood extends downward from the point of junction with the top or cover, 12, for only a portion of the distance from the cover to the bottom of the box frame, leaving an open 90 space between the lower line of the side, 10, and the front longitudinal, 16, which space serves as the hot air outlet, 13, of my dust 95 hood.

The top or cover, 12, preferably is convex 100 or curved, upwardly, when viewed in cross section, to afford by reason of its interior concavity a means of deflecting downwardly the hot air received through the open bottom of the box frame. The cover, 12, as shown 105 in the drawings, is fixedly attached to the sides, 10, and ends, 11, but it may be hinged at its rear and provided on its front with a latch or catch to secure the top or cover to the box frame and to permit opening of the 110 cover, 12, the more readily to clean the interior of my dust hood of ashes, dust or similar matter.

The air screening ledge or shelf, 14, is provided with wire gauze or other closely 115 meshed material which will permit the passage of the hot air therethrough, but will re-

tain ashes, dust, lint or similar substances. The air screening ledge or shelf, 14, is supported in the box frame longitudinally or horizontally of the box frame on or slightly 5 above the upper longitudinal line of the hot air outlet, 13, the ledge or shelf, 14, extending inwardly in width into the interior of the box frame for only a portion of the width of the box frame, the intention being 10 that the ledge or shelf, 14, should be located adjacent to the hot air outlet, 13, in such position as to receive and screen the deflected hot air in the hood before its passage through the hot air outlet, and yet not interfere with or screen the hot air as it is received directly from the register or radiator, 15 as such interference or screening would cause the ashes, dust or similar matter to drop back into the register or radiator instead of finding lodgment on the ledge or shelf, 14. The ledge or shelf, 14, is inclined downwardly toward its inner edge the better 20 to receive and screen the deflected hot air, its inner edge being slightly raised or beaded to retain the ashes, dust and similar matter on the ledge or shelf.

The water trough, 15, is arranged longitudinally of the box frame near the bottom thereof on the side opposite the air 30 screening ledge or shelf, 14. The water trough, 15, is open at its top to allow the moisture therefrom to mingle with the hot air, and is provided at one end with an extension, 18, projecting through one end, 11, 35 of the box frame to permit the water trough to be supplied with water from the exterior of my dust hood. By placing the water trough, 15, near the bottom of the box frame, I afford greater steadiness to my dust hood 40 in its position over the register or radiator.

In use my dust hood is placed over the register or radiator so that the hot air therefrom is received through the open bottom, moistened by the water in the trough, 15, 45 and deflected by the top or cover, 12, upon the ledge or shelf, 14, which screens it before its passage through the hot air outlet, 13, the dust, ashes or similar matter clinging to the interior of the top or cover, 12, and 50 being retained also on the ledge or shelf, 14, whence it subsequently can be removed from the dust hood.

For use with a side wall register or radiator, my dust hood may be raised sufficiently 55 to cover the hot air area of the wall register or radiator by extending downwardly the front longitudinal, 16, as an addition to the side, 10, of the box frame, below the outlet, 13, and each end, 11, downwardly, thereby 60 forming a stand or support for the dust hood, open at its back to receive the hot air from the wall register or radiator and which will also collect the hot air therefrom and transmit it to my dust hood through the 65 open bottom thereof.

In using my dust hood on an oil or gas heater, it may be placed on the top thereof, it being constructed of sufficient size substantially to cover the top of such heater, the hot air being collected in the dust hood and 70 moistened by the water in the trough thereof and distributed in the room from the hot air outlet in direction in accordance with the position of my dust hood on the heater.

Having fully described my invention, I 75 claim:

1. A dust hood for hot air registers comprising a box frame open at its bottom to receive the hot air from the register and having a hot air outlet, a deflecting cover 80 for the box frame, and a reticulated shelf in width less than the width of the box frame arranged therein adjacent to the hot air outlet whereby the hot air from the register is screened before passage thereof through the hot air outlet; substantially as set forth.

2. A dust hood for hot air registers comprising a box frame open at its bottom to receive the hot air from the register and having a hot air outlet, a deflecting cover for the box frame, a reticulated shelf in width less than the width of the box frame arranged therein adjacent to the hot air outlet whereby the hot air from the register is screened before passage thereof through the hot air outlet, and means for moistening the hot air before passage thereof through the hot air outlet; substantially as set forth.

3. A dust hood for hot air registers comprising a box frame open at its bottom to receive the hot air from the register and having a hot air outlet, a deflecting cover for the box frame, and a reticulated shelf in width less than the width of the box frame arranged therein on or slightly above the upper line of the hot air outlet whereby the hot air from the register is screened before passage thereof through the hot air outlet; substantially as set forth.

4. A dust hood for hot air registers comprising a box frame open at its bottom to receive the hot air from the register and having a horizontal hot air outlet, a deflecting cover for the box frame, and a reticulated shelf in width less than the width of the box frame arranged horizontally therein adjacent to the hot air outlet whereby the hot air from the register is screened before passage thereof through the hot air outlet; substantially as set forth.

5. A dust hood for hot air registers comprising a rectangular box frame open at its bottom to receive the hot air from the register and having a longitudinal hot air outlet, a deflecting cover for the box frame, and a reticulated shelf in width less than the width of the box frame supported therein longitudinally thereof on or slightly above the upper line of the hot air outlet whereby

the hot air from the register is screened before passage thereof through the hot air outlet; substantially as set forth.

6. A dust hood for hot air registers comprising a rectangular box frame open at its bottom to receive the hot air from the register and having a longitudinal hot air outlet at one side near the bottom thereof, an upwardly curved cover for the box frame, and a shelf in width less than the width of the box frame supported therein longitudinally thereof on or slightly above the upper line of the hot air outlet and provided with wire gauze or other closely meshed material; substantially as set forth.

7. A dust hood for hot air registers comprising a rectangular box frame open at its bottom to receive the hot air from the register and having a longitudinal hot air outlet at one side near the bottom thereof, an upwardly curved cover for the box frame, and a shelf in width less than the width of the box frame supported therein longitudinally thereof on or slightly above the upper line of the hot air outlet, said shelf being inclined downwardly toward its inner edge

and provided with wire gauze or other closely meshed material; substantially as set forth.

8. A dust hood for hot air registers comprising a rectangular box frame open at its bottom to receive the hot air from the register and having a longitudinal hot air outlet at one side near the bottom thereof, means for strengthening the box frame longitudinally and transversely, an upwardly curved cover for the box frame, a shelf in width less than the width of the box frame supported therein longitudinally thereof, on or slightly above the upper line of the hot air outlet, said shelf being inclined downwardly toward the inner edge and provided with wire gauze or other closely meshed material, and a water trough arranged longitudinally in the box frame on the side thereof opposite said shelf having means for supplying water thereto; substantially as set forth.
